UNITED STATES PATENT OFFICE.

WILLIAM ANSELM COATES, OF CHORLTON-CUM HARDY, AND GEORGE EDWARD GITINS AND DAVID REGINALD DAVIES, OF STRETFORD, MANCHESTER, ENGLAND, ASSIGNEES TO WESTINGHOUSE ELECTRIC AND MANUFACTURING COMPANY, A CORPORATION OF PENNSYLVANIA.

ELECTRIC SWITCH.

Application filed June 5, 1922, Serial No. 566,031, and in Great Britain July 13, 1921.

Our invention relates to electric-switch operating mechanisms and particularly to means for operating a plurality of associated switches in a predetermined relation.

In electrical distributing systems, two sets of bus-bars are very often provided for connection either to a generator or to a feeder or distributing circuit, for example, and switches commonly known as selector switches are provided by means of which either one set of bus-bars, which may be called the main bars, or the other set of bars, which may be called the auxiliary bars, may be used, as desired. The selector switches have a common terminal which is connected, through an isolating switch, to the conductor leading from the generator or the feeder leading to the distributing system, as the case may be. An oil switch is inserted between the isolating switch and the selector switches on both sides of the bus-bars. Where a split conductor system is employed, two isolating switches will be provided, one in each portion of the conductor.

The object of the present invention is to provide an improved construction by means of which, in a system similar to that above described, the isolating switch and one or the other of the selector switches, as desired, may be operated by means of a single operating shaft or handle.

According to the invention, the main operating shaft of the switching apparatus is arranged to close one selector switch when turned in one direction from a mean position and to close the other selector switch when turned in the other direction, the isolating switch being adapted to be closed when the main shaft is turned in either direction.

To enable the invention to be clearly understood, a construction of isolating and selector switches, together with operating mechanism in accordance with the invention will now be described with reference to the accompanying drawings, in which,

Fig. 1 is an electrical diagram illustrating also, by way of example, one use of the switches of the kind to which the invention relates,

Fig. 2 is a view, in side elevation, of the

isolating and selector switches and the operating mechanism.

Fig. 2 is a similar view showing the selector switches in different positions, and

Fig. 4 is a detailed perspective view showing the operating cranks of the switches separated for convenience of description.

Referring first to Fig. 1, a three-phase cable 1 having conductors 2 or three separate conductors 2, may be connected by means of a main oil switch or circuit breaker 3 alternatively with a set of main bus-bars 4 or a set of auxiliary bus-bars 5. The arrangement for one of the cable phase conductors 2 only is shown, it being considered unnecessary to illustrate the others since they are connected in exactly similar manner. One of the conductors 2 is shown as connected to a terminal 6 of the oil switch 3 by means of an isolating switch 7. It will be understood that where split conductors are provided there will be two isolating switches 7 which will be simultaneously operated for connecting the splits to the terminal 6 which will itself be split. The other terminal 9 of the oil switch 3 may be connected either with one of the main bus-bars 4 by means of a main selector switch 10 or with one of the auxiliary bus-bars 5 by an auxiliary selector switch 11. It will be further understood that the invention is in no way limited to three-phase systems.

Reference will now be made to Figs. 2 and 3 wherein is illustrated, as already mentioned, the improved construction of the switches operating in accordance with the invention. The two selector switches 10 and 11 are in this case arranged side by side in one end of a container 12 such as an oil tank, whilst the isolating switch 7 is disposed in the other end of said container or oil tank. In the case of split conductors, the two isolating switches 7 may be disposed side by side in a similar manner to the selector switches 10 and 11. The main operating shaft of the switches is indicated at 13 symmetrically disposed between the isolating and selector switches and, in the particular form illustrated, above the switch head or casting 14 which latter may be of any convenient construction and supported as desired. In some cases, the main shaft 13

may be disposed within the tank. All the switches are of the same general description and this being the case only one of them will be described in detail, namely, the isolating switch 7.

The bridges of the switches are preferably of the laminated-brush type, the laminations being clamped between rigid supporting members 16 and 17. Two such bridges 16 are preferably employed in each switch arranged substantially vertically and adapted to be moved in a substantially horizontal direction in relation to a pair of fixed contact members 18 and 19. The fixed contact member 19 is disposed substantially vertically above the contact member 18 and is supported at a convenient distance from the latter.

The contact members 18 and 19 are supported by concentric conductors suitably insulated from one another, that is to say, the lower contact member 18 is connected to the end of an insulated rod 20 that passes through a tubular conductor 21 which carries, at its end, the contact member 19 and is suitably insulated. The concentric conductors are passed through a perforation in the switch head or casting 14 and are supported therein by means of a bushing 22 or in any other convenient manner.

The above described arrangement of the conductors 20 and 21 and certain of the switch operating devices forms the basis of our co-pending application, Serial No. 566,632, filed June 5th, 1922, and is particularly appropriate for the vertical dispositions of the contact members 18 and 19.

The two bridge members 7 simultaneously engage the contact members 18 and 19, symmetrically, at opposite sides thereof and the said contact members may be of equal width but, as shown, the contact member 19 is preferably of greater width than the lower contact member 18 and the faces of both contacts are in planes which make a small angle with the center line of the conductors 20 and 21.

The outer support members 17 of the laminated brushes 7 forming the bridges are pivotally supported at 23 upon lever members 24 which are of substantially triangular shape and in action constitute bell-crank levers. The lever members 24 are both pivoted at 25 to a lug which is preferably integral with the lower contact 18 and extends underneath the latter. The tail portions 26 of the lever members 24 are connected together by a pair of toggle links 27 and 28 which are pivoted together at 29. When the toggle is substantially straight, the tail portions 26 of the members 24 will be forced outwards and upwards about the common pivot 25 of the members 24 whilst the upper ends of the latter will be forced towards one another so that the

bridge members 7 of the switch are brought into engagement with the fixed contacts 18 and 19 of the switch. The toggle links 27 and 28 thus permit the switch to be closed with considerable force.

For operating the switch in the above manner, one of the links 27 or 28 is provided with a lever extension 32 beyond its pivotal connection 26 to the associated lever member 24, the said extension 32 being connected by means of an adjustable insulating connecting rod 33 with a crank 34 mounted upon the switch-operating shaft 13. With this arrangement, when the crank 34 is operated to raise the rod 33, the switch is closed and, when the crank 34 is then moved in a reverse direction or released, the link 33 falls and the toggle links 27 and 28 collapse in an upward direction and the bridges 7 separate from the fixed contacts 18 and 19.

Attention is here directed to the similarly constructed selector switches 10 and 11 shown respectively one in front of the other at the left hand side in Figs. 2 and 3. In Fig. 2 the main selector switch 10 is shown closed, its toggle links being straightened out whilst it will be observed that the bridges 11 of the auxiliary selector switch are open, the toggle links of this switch being collapsed. In Fig. 3, the bridges 10 of the main selector switch are open whilst the bridges 11 of the auxiliary selector switch are in the closed position. The lever members 24 advantageously each comprise two plates which embrace the outer brush support 17, the toggle links 27 and 28 and the common pivot 25. It will be noted that the lever extensions 32 of all the switches extend inwards approximately into a vertical plane passing through the operating shaft 13.

The isolating and selector switches above described are operated in the following manner, attention being now more particularly directed to Fig. 4. The three operating toggle levers 32 of each of the switches, that is, one isolating switch and two selector switches, are connected to corresponding cranks 34, 35 and 36 by means of the connecting links 33. The central crank 34 for the isolating switch is keyed to the operating shaft 13, as shown in dotted lines in Fig. 4, and its hub is provided with projections 37 and 38 on opposite sides thereof as shown.

The other cranks 35 and 36 which operate, respectively, the selector switches 10 and 11 are loosely mounted on the shaft 13 one on each side of the crank 34 of the isolating switch. The left hand crank 35 (Fig. 4), which operates the main selector switch 10, is provided on one side of its hub with a projection 39 which, when the cranks are vertically downwards, is angularly displaced with respect to the projection 37 on the cen-

tral crank. Similarly, the right hand crank 36 pertaining to the auxiliary selector switch is provided on its hub with a projection 40 which is angularly displaced by 180° with respect to the projection 39 on the left hand crank 35.

In Fig. 4, the three cranks have been spaced apart for the purpose of clear illustration and description, as already stated.

10 Actually the said cranks are adjacent one another so that the projection 37 will engage the projection 39 when the shaft 13 is rotated in the counter-clockwise direction (as seen from the left of Fig. 4) so that both these 15 cranks will be rotated from their normal downwardly depending positions into the elevated position shown in Fig. 2, and the isolating switch 7 and the main selector switch 10 are simultaneously closed. The 20 projection 38 does not engage the projection 40 so that the auxiliary selector switch 11 is not operated. If, on the other hand, the shaft 13 is rotated in the clockwise direction, the projection 37 will not engage the projection 25 39, but the projection 38 will engage the projection 40 so that the cranks 34 and 36 are moved to the position illustrated in Fig. 3 and the isolating and auxiliary selector switches are simultaneously closed, the main 30 selector switch now remaining open.

The shaft 13 may be turned in any convenient manner, for example, by means of a simple crank handle or through the intermediary of switch-operating mechanism of any desired description (not illustrated). The projections 37 to 40 are preferably so spaced and proportioned that a certain amount of lost motion is provided between the movements of the middle crank and the outer ones, in order to avoid the tendency 40 for three switches to begin to move at one time.

In the case of a split conductor system the second isolating switch may be arranged by 45 the side of the one illustrated in the drawing, that is to say, in line with the auxiliary selector switch 11, and may be operated by

the crank 34 or another crank keyed on the main operating shaft. It will be understood, however, that any or all of the switches 50 may be disposed in separate tanks or otherwise arranged.

Preferably, the lever members 24 are provided with faces 43 which engage the bottom surface of the fixed contact member 18, thereby limiting the outward movement of the members 24.

It will be understood that various modifications may be made in the construction and arrangement of the switches and operating 60 mechanism without departing from the scope of the invention. For example, the invention is not limited to the type of switches described and illustrated, it being obvious that the cranks 34, 35, and 36 may operate 65 switches with horizontally disposed bridges.

We claim as our invention:

1. The combination with three switches, of an operating shaft for closing the several switches, a crank mounted on and fixed to 70 the shaft for controlling one of the switches during movement of the shaft in either direction, and cranks loosely mounted on the shaft and actuated by the first named crank for controlling the other switches in accordance with the direction of movement of the shaft.

2. The combination with three switches, of an operating shaft for closing the several switches, a crank mounted on and fixed to 80 the shaft for controlling one of the switches during movement of the shaft in either direction, and cranks loosely mounted on the shaft and actuated by the first named crank for selectively controlling one of the switches 85 during movement of the shaft in either direction.

In testimony whereof we have hereunto subscribed our names this 18th day of May, 1922.
